Nicholas W. Akimoff,
By J. Walter Douglas,
Attorney.

UNITED STATES PATENT OFFICE.

NICHOLAS W. AKIMOFF, OF PHILADELPHIA, PENNSYLVANIA.

MECHANICAL SPEED-GOVERNOR.

SPECIFICATION forming part of Letters Patent No. 785,587, dated March 21, 1905.

Application filed January 21, 1905. Serial No. 242,050.

To all whom it may concern:

Be it known that I, NICHOLAS W. AKIMOFF, a subject of the Czar of Russia, residing at the city of Philadelphia, in the county of Philadelphia and State of Pennsylvania, have invented certain new and useful Improvements in Mechanical Speed-Governors, of which the following is a specification.

My invention has relation to a mechanical speed-governor, and in such connection it relates more particularly to a gyroscopic device adapted to be employed in conjunction with such a governor.

The principal objects of my invention are, first, to provide a governor for slow-speed engines of any type with a gyroscopic device adapted to prevent undesirable fluctuations therein, and, second, to provide for this purpose a governor with a disk adapted to be flexibly and pivotally secured thereto and by its resistance to change in its plane of rotation to counteract and thereby eliminate superfluous sensibility of the governor.

As is well known, dash-pots have hitherto been employed to overcome the foregoing objectionable features of governors for slow-speed engines in the racing up and down of its axis of rotation. Such dash-pots, however, are costly as to installation and maintenance and require constant vigilance, so as to insure proper operation.

The nature, scope, and characteristic features of my invention will be more fully understood from the following description, taken in connection with the accompanying drawing, illustrating, partly in elevation and partly in section, a governor with a disk in pivotal and flexible connection therewith embodying main features of my present invention.

Referring to the drawing, *a* is a housing secured to an engine. (Not shown.) In the housing *a* is arranged a shaft *b*, which is rotated by a pulley *b'*, driven by any rotating part of the engine. (Not shown.) The rotary movement of the shaft *b*, by means of gear-wheels *c* and *c'*, is transmitted to a spindle *d*, arranged in the housing *a*, from the free end of which is pivotally suspended arms *d'* and *d''*, carrying the centrifugal balls *d''*

and *d''*. Arms *d'* and *d''* pivotally connect the 50 arms *d'* and *d''* with a sleeve *e*, carrying a weight *e'*, both having a range of sliding movement on the spindle *d*. The sleeve *e* is provided with an annular groove *e'*, adapted to receive a lever *f*, having its fulcral point 55 *f'* in a bracket *a'* of the housing *a*. One end of the lever *f*, by means of a rod *f''*, is connected, for instance, with the throttle-valve of a steam-engine, (not shown,) while the other end, by means of a link *f'''*, is pivotally 60 connected with a shaft *g*. The shaft *g*, by means of a universal joint *g'*, is connected with a shaft *h*, preferably supported by a sleeve *a''* and arm *a''*, which is suitably secured to the housing *a*. The shaft *h* is provided 65 with a sprocket-wheel *h'*, which by means of a sprocket-chain *h''* is connected with a sprocket-wheel *h''*, secured to the shaft *b*. On the shaft *g* is rigidly secured a disk or fly-wheel *g''*, which on account of its flexible connection with the shaft *h* may assume varying 70 angular positions thereto, but normally in its operative position occupying approximately a position parallel to the spindle *d*. When the shaft *b* is rotated, its movement is transmitted to the spindle *d*, and the sleeve *e* and weight rise and fall by the intervention of the arms *d'*, *d''*, *d''*, and *d''* and its balls *d''* and *d''* in the usual well-known manner. This movement of the sleeve *e*, by means of the lever *f*, 75 is transmitted to the shaft *g* and disk *g''* and by this movement will be held in varying angular positions with respect to the spindle *d*. The disk *g''*, however, being set in rapid rotation by the shaft *b* resists a quick change in 80 its plane of rotation and in this manner effectively prevents any sudden movement of the sleeve *e* on the spindle *d*, rendering the governor more stable in its action. Any tendency of the governor to change its position 85 on the spindle *d* in a certain definite length of time—for instance, to automatically readjust the position of a throttle-valve—is not resisted by the disk *g''*, but is readily permitted by the same. The object of the disk *g''* is solely 90 to prevent undesirable sudden fluctuations of the governor in its action.

Having thus described the nature and ob-

jects of my invention, what I claim as new, and desire to secure by Letters Patent, is—

1. In a speed-governor, a spindle, a sleeve 5 slidably arranged on said spindle, means having centrifugal balls connecting said sleeve with said spindle, means adapted to rotate said spindle, sleeve and balls, a disk, a shaft carrying said disk, means adapted to connect said shaft with said sleeve, means adapted to rotate said shaft and disk, and said disk when rotated adapted to prevent sudden movements of said sleeve on said spindle.

2. In a speed-governor, a spindle, a sleeve 15 slidably arranged on said spindle, means having centrifugal balls connecting said sleeve with said spindle, means adapted to rotate said spindle, sleeve and balls, a disk, a shaft adapted to hold said disk in varying angular and parallel positions with respect to said spindle, 20 means adapted to connect said shaft with said sleeve, means adapted to rotate said shaft and disk, and said disk when rotated adapted to control the sudden movement of said sleeve on said spindle by its resistance to change in 25 its plane of rotation.

3. In a speed-governor, a spindle, a sleeve 30 slidably arranged on said spindle, means having centrifugal balls connecting said sleeve with said spindle, means adapted to rotate said spindle, sleeve and balls, shafts flexibly connected with each other, a disk arranged on one 35 of said shafts and held by the same parallel and in varying angular positions with respect to said spindle, means adapted to connect said disk-shaft with said sleeve, means adapted to rotate said shafts and disk, and said disk when rotated adapted to prevent sudden movement of said sleeve on said spindle.

4. In a speed-governor, a spindle, a sleeve 40 slidably arranged on said spindle, means con-

necting said sleeve with said spindle, shafts 45 flexibly connected with each other, a disk carried by one of said shafts and held by the same parallel and in varying angular positions with respect to said spindle, means adapted to connect said disk-shaft with said sleeve, means adapted to rotate said shafts and disk and said spindle independently of each other, and said disk, when rotated, adapted to control the sudden movement of said sleeve on said spindle 50 by its resistance to change in its plane of rotation.

5. In a speed-governor, a housing, a spindle arranged therein, a sleeve slidably arranged on said spindle, means connecting said sleeve 55 with said spindle, shafts partially supported by said housing, a universal joint connecting the shafts with each other, a disk carried by one of said shafts and held by the same parallel and in varying angular positions with 60 respect to said spindle, means adapted to connect said shafts with said sleeve to partially support one of said shafts and its disk by said sleeve, a driving-shaft supported by said housing adapted to rotate said spindle, sleeve and 65 balls, means connecting the driving-shaft with one of the disk-shafts and adapted to rotate the same and disk with a speed greater than that of said spindle, and said disk when rotated adapted to check the sudden movements 70 of said sleeve on said spindle by its resistance to change in its plane of rotation.

In testimony whereof I have hereunto set my signature in the presence of two subscribing witnesses.

NICHOLAS W. AKIMOFF.
